2 SHEETS—SHEET 2.

FIG. 3.

UNITED STATES PATENT OFFICE.

JOHN E. FREY AND THOMAS F. BERRILL, OF NEW YORK, N. Y.

SHEET-METAL-DOOR CONSTRUCTION.

1,161,121.

Specification of Letters Patent. Patented Nov. 23, 1915.

Application filed April 17, 1915. Serial No. 22,198.

To all whom it may concern:

Be it known that we, JOHN E. FREY and THOMAS F. BERRILL, citizens of the United States, and residents of New York, borough of Brooklyn, county of Kings, State of New York, have invented certain new and useful Improvements in Sheet-Metal-Door Construction, of which the following is a specification.

10 Our invention relates to doors and has particular reference to hollow steel doors and sashes and the panel construction therein, but it will be understood that some of the novel features of the invention are applicable in panel construction generally.

The primary object of the invention is to provide novel means for joining the parts of the door together and for holding the panel in place. The interlocking parts are greatly simplified and consequently they are less expensive to make and assemble. The construction of the glass molding and glazing strip which holds the glass is a novel feature. The means by which the parts are 25 fastened together without the necessity of rivets, screws or bolts provides a cheap and efficient method of construction.

The above and other objects and the novel features of the invention will appear from 30 the following description taken in connection with the drawing.

Figure 1 is a perspective view of a door embodying our invention; Fig. 2 is an enlarged vertical section of the door, taken on 35 the line 2—2 of Fig. 1 with parts thereof broken out and parts removed; Fig. 3 is an enlarged transverse section taken on the line 3—3 of Fig. 1; Fig. 4 is a sectional view taken transversely of the joint between a 40 stile and a rail, and on the line 4—4 of Fig. 1; Fig. 5 is a perspective view showing the method of interlocking the uniting key with the stiffening channel, the parts being slightly separated; Fig. 6 is a perspective 45 view of a portion of a stile coped to receive rails; Fig. 7 is a perspective view of a portion of the glass molding and glazing strip; and Fig. 8 is a sectional view showing a 50 single thin sheet panel construction for rails or stiles.

Referring to the drawings 10 and 11 designate the stiles of the door or panel and 12 and 13 designate the top and bottom rails which are united to the ends of the stiles.

55 Referring to Fig. 6, each of the stiles is

made of sheet metal and has an end 14 and parallel sides 15. At the upper and lower ends of each stile the sides 15 are bent inwardly as at 16 to provide flanges which form shoulders on the interior of the hollow 60 stile.

Between the flanges 16 at the opposite ends of the stile the sides 15 are bent inwardly as at 17 to form shoulders on the interior of the stile which are in fact a continuation of the shoulders 16 at the ends of the stile, whereby a substantially continuous shoulder is formed on each side 15 throughout the length of the stile. A beveled or ornamental molding 18 is formed at the free 65 edge of the shoulder 17 and integral with the sides 15. The molding 18 extends inwardly and its free edge is bent outwardly as at 19 to provide a locking groove 20 at the outer end of the moldings on the side members 15. 70 In Fig. 6 the grooves are shown as opening outwardly, but it will be understood that they may also be formed to face each other as shown in the upper part of Fig. 2.

A stiffening channel 21 shown in perspective in Fig. 5 is designed to fit between the sides 15 of the stile, being provided with parallel flanges 22 at its free edges which engage the inner surfaces of the side walls 15. The stiffening channel is formed from 85 a single plate of sheet metal and is bent to provide a depressed portion or channel 23 extending longitudinally thereof at its center. The side walls 24 of the channel have laterally extending flanges 25 which fit 90 against the shoulders 17 and hold the channel in place. The channel is inserted into the stile through the end of the latter and it spans the space between the side walls 15.

A key 26 unites the channel and the outer 95 ends of the moldings 18. As shown in Fig. 5 the uniting key comprises a single metal plate shaped so as to form a substantially rectangular central portion, the base 27 of which has the oppositely disposed tongues 28 struck therefrom. The tongues 28 are constructed to fit into slots 29 in the bottom 30 of the channel on the stiffening member 21. The parts 21 and 26 are fastened together by fastening the tongues 28 into the 100 slots 29 and bending the tongues in opposite directions thereby preventing relative movement between the two and securely uniting the stiffening channel and key. The base 27 of the key is of such width as to fit snugly 105 110

- into the channel 23 and the side walls 31 fit against the sides 24 of the channel. The key has two spaced parallel walls 32 which are joined to the walls 31 by the shoulders 33. The outer free ends of the walls 32 are provided with flanges 34 which extend outwardly and at the outer ends of the flanges 34 the metal is bent rearwardly parallel to the walls 32 as at 35 and then inwardly as at 36 whereby grooves 37 are provided to receive the edges of the flanges 19 at the free edges of the moldings 18. The inter-engaging hooked portions at the edges of the key 26 and moldings 18 interlock the parts together, conceal the raw metal edge of the shoulder 49 and provide a rigid structure and one which is readily assembled without the necessity of drilling, tapping or drawing the members.
- 20 The panel 38 which is supported by the key may be a plate of glass, wood, asbestos or other suitable material. The right hand side of Fig. 3 illustrates an asbestos panel 38 which has veneering secured to the opposite sides thereof and composed of thin sheet metal plates 39 provided with flanges 40 at their edges which extend beneath the shoulders 33 and serve to retain the panel in position.
- 25 30 When glass panels are used a panel molding is provided which is illustrated in perspective view in Fig. 7 and consists of two plates. The glass molding strip has a base portion 41 shaped similar to the base of the uniting key 26, but smaller so that it will slide into the base of the uniting key. The shoulders 42 on the glass molding strip engage against the shoulders 33 of the uniting key and the molding strip is thereby locked in place.
- 35 40 Two parallel faces 43 and 44 are formed at the inner edges of the shoulders 42 and are spaced apart and when in position they engage against the parallel faces 32 of the uniting key. The outer edge of the face 43 has an outwardly extending flange 45 which when in position is spaced from one of the flanges 34 on the uniting key and the flange 46 at the inner end of an adjustable glazing strip 47 is clamped between the flange 45 and the adjacent flange 34. The flange 46 on the glazing strip 47 constitutes one side of a groove at the inner edge of the glazing strip, the other side of the groove being designated by the numeral 48 and being somewhat shorter than the flange 45 leaving a shoulder 49 at the inner edge thereof to support the glass panel 381. At its outer free edge the glazing strip has a bead 50 and between the bead 50 and the wall 48 there is a flat part 51 which fits against one side of the glass panel. The face 44 of the glass molding fits against the opposite side of the glass panel and has a bead 52 at its outer end located opposite the bead 50 on

the glazing strip. The glazing strip and glass molding are only spaced apart a distance sufficient to receive the glass panel and will provide a rigid supporting and retaining means for the panel.

70 In Fig. 8 we have shown a modified form of device for retaining a single sheet panel 382 in place. The adapter for the panel 382 comprises a sheet metal member which has a channel 53 extending longitudinally thereof and located midway between its sides. The plate on the opposite side of the channel is bent upon itself to provide the rearwardly extending legs 54 of the adapter and the free ends of the members 54 are 75 bent upwardly at an angle as at 55. The upwardly extending parts 55 of the adapter engage the shoulders 33 of the uniting key 26 to lock the adapter to the stile. The panel 382 may readily be forced into the 80 channel 53 when the parts have been assembled. A gasket may be inserted in the interior grooves provided by the beads 50 and 52 to frictionally engage the glass panel.

90 Referring to Fig. 4 the side walls 57 of the rails are bent at their ends to form the inwardly extending portions 58 and the rearwardly extending portions 59 to provide hooked portions at the ends of the side walls 95 to receive the hooks 60 on the rail-hooks 61 which have laterally and inwardly extending flanges 62 constructed to fit against the flanges 25 at the lower ends of the stiffening member 21. The flanges 62 of the rail-hooks 100 are provided with slots corresponding to the slots 29 of Fig. 5 to receive the tongues 63 punched from the faces 25 of the stiffening channel 21. The free ends of the tongues 63 are bent against the outside 105 faces of the portions 62 to connect the rail-hooks and stiffening channels and thereby unite the rails and stiles. The rail hooks 61, 61 and the slotted base portions 62 thereof are made from a single piece of sheet 110 metal. The flanges 16 abut against the inwardly extending portions 58 on the ends of the rails and a close fitting joint is thereby provided between the rails and stiles.

115 It will be understood that the joint between the rails and stiles shown in Fig. 4 is duplicated on the opposite end of the rail. As shown in Fig. 2 the upper edge of the rail 18 and the lower edge of the rail 12 is constructed in the same manner as the panel 120 supporting edge of the stiles heretofore described and there will therefore be no need of repeating the description of the construction shown. The top and bottom edges of the hollow stiles and rails may be closed by 125 means of a channel member 65 and plate 66 which are suitably secured in the open ends.

130 While we have shown and described the construction in detail it will be understood that we do not wish to be limited to the

exact details as shown, as they may be varied without departing from the spirit of the invention.

What we claim is:—

- 5 1. In panel construction, the combination of a hollow side member having spaced side walls, moldings at the edges of said walls, a bracing member fitting between said side walls, a panel supporting device having a 10 part fitting between said moldings, a key member having interfitting engagement with said device, and tongue and slot connections between said bracing member and key member. 70
- 15 2. In panel construction, the combination of a hollow side member having spaced walls provided with parts which extend toward one another and form shoulders, molding members connected with said walls and provided 20 with locking means at their free edges, a bracing member fitting against said shoulders and spanning the space between said walls, a panel supporting device having a part extending into the space between said 25 molding members, and a key engaged by the locking means at the edges of the molding members and connected to said bracing member, said key fitting between said molding members and the panel supporting device and holding the latter in place. 80
3. In panel construction the combination of a hollow side member provided with spaced walls having shoulders extending longitudinally thereof within said side members, moldings having edges spaced apart and provided with locking means, a bracing member for said side member fitting against said shoulders and having a channel extending longitudinally thereof, a hollow key 35 member having an enlarged part fitting in said channel and secured to said bracing member, said key member having parts interlocking with the locking means on the moldings, and a panel supporting device 40 having a part fitting in the enlarged part of the hollow key member and held in place thereby, said key member being located between the panel supporting device and said moldings. 100
4. In panel construction the combination of a hollow rail or similar member having lateral shoulders extending longitudinally thereof and moldings, a stiffening member for said rail or similar member fitting against 45 said shoulders, a panel supporting member and a key secured to said stiffening member, said key being provided with portions for interlockingly engaging said moldings and panel retaining member. 105
5. In panel construction, the combination of a hollow side member having side walls provided with inner edges, and moldings attached to said inner edges, said moldings extending inwardly toward each other, leaving 50 a space between them and having their free 110
- edges disposed outside said space and bent to form locking grooves open at the outer sides of the moldings and a panel supporting device comprising a part which has edges interfitting with the free outer edges of the moldings to conceal the raw edges on said moldings and device. 115
6. In panel construction, the combination of a stile having spaced side walls and moldings at the inner edges of said side walls, 75 said moldings terminating at a distance from the ends of said side walls, the free edges of the moldings being spaced apart, a bracing member located between said side walls and extending beyond the ends of the moldings, a panel retaining member between said moldings and secured to said bracing member, a rail, and means for connecting the end of said rail to one end of said bracing member beyond the ends of said moldings. 85
7. In panel construction, the combination of a stile having spaced walls provided with longitudinally extending shoulders, a bracing member between said walls and fitting against said shoulders, a rail having spaced walls terminating at their opposite ends in inturned edges which have parts abutting against the outside surfaces of said shoulders, and means for fastening said rail to 90 said stile comprising parts which engage said inturned edges and said bracing members. 95
8. In panel construction, the combination of a side member, a panel retaining member, a glazing strip, outside the panel retaining member and having a part thereof adapted to engage against the face of the panel said glazing strip and the panel retaining member having interfitting edge portions 100 adapted to join the glazing strip to the panel supporting member, said interfitting portions having their raw metal edges concealed, and means for securing the panel retaining member in place on the side member. 105
9. In panel construction the combination of a hollow side member having an integral molding formed thereon, the free edge of the molding being provided with locking portions, and lateral flanges extending 110 longitudinally of said side member beyond the ends of the molding, a stiffening member disposed within said hollow member and fitting against said shoulders, and a device fastened to said stiffening member and having parts interlocking with the locking portion on the molding of the side member. 115
10. In panel construction, a side member having interior flanges forming lateral shoulders extending longitudinally thereof, moldings located intermediate the ends of said side member and formed integral therewith, each of said moldings having a locking portion at its free edge, a stiffening de- 120
- 125
- 130
- 135
- 140

vice within said side member and fitting against said shoulders, and a locking device secured to said stiffening device and having parts interfitting with the locking portions of said molding.

11. In panel construction the combination of a stile having lateral flanges forming shoulders, a stiffening member fitting against said shoulders, a rail having lateral shoulders, and a device engaging the shoulders on the rail and secured to said stiffening member.

12. In panel construction the combination of a hollow stile having longitudinally extending shoulders, a stiffening member within the stile, a rail having flanges at its ends abutting against the flanges on the stile, and hooked devices interlocking with the flanges on the rail, and connected with said stiffening member.

13. In panel construction the combination of a hollow member having longitudinally extending shoulders and moldings connected to said shoulders, a stiffening device fitting against said shoulders, a key connected to said stiffening device and interlockingly engaging with said moldings, a panel and a panel retaining device fitting said key and having edge portions thereof interlocking with portions of said key to hold the panel retaining device in position.

14. In panel construction the combination of a hollow stile or similar member having longitudinally extending flanges providing shoulders, and moldings connected to said flanges and having locking portions at their free ends, a stiffening member within the hollow stile and fitting against said shoulders, a key secured to said stiffening member and interlocking with said moldings, a panel, and means for retaining said panel comprising a device held in place by said key and engaging the panel on one side, and a strip clamped between said device and key and engaging the panel on the opposite side.

15. In panel construction, the combination of a stile and a rail, the edges of which abut, one of said edges providing an in-

terior shoulder and the other having an interior locking portion, a device fitting against the shoulder, and a locking member having a part secured to said device and a part interlocking with said interior locking portion.

16. In panel construction, the combination of a stile having spaced walls provided with longitudinally extending inturned shoulders, a member spanning the space between said walls and fitting against said shoulders, a rail having spaced walls terminating in interior locking grooves which abut against said shoulders, and a channel member for fastening said rail to said stile comprising parts having hooked portions interlocking with said grooves and portions which are rigidly united with said member.

17. In panel construction, the combination of a hollow stile or rail having spaced side walls, a bracing member between said side walls, a molding, a panel supporting member having a part interlocking with a part on said molding, and means connecting said members comprising tongues punched from one member fitting slots punched in the other member, said tongues being spread in opposite directions and flattened so as to unite said members.

18. In panel construction, the combination of a side member having spaced side walls provided with longitudinally extending shoulders, a stiffening member spanning said walls and fitting against said shoulders, a panel supporting member having a longitudinally extending panel receiving groove between its sides, and a hollow key interlockingly engaging the sides of said panel supporting member and united with said stiffening member, said sides of the panel supporting member being disposed within said key.

In testimony whereof we affix our signatures in presence of two witnesses.
